UNITED STATES PATENT OFFICE.

HENRY DETJEN, OF MANITOWOC, WISCONSIN.

COUPON-CUTTING DEVICE.

1,416,800.

Specification of Letters Patent. Patented May 23, 1922.

Application filed December 21, 1920. Serial No. 432,213.

To all whom it may concern:

Be it known that I, HENRY DETJEN, a citizen of the United States, and resident of Manitowoc, in the county of Manitowoc and State of Wisconsin, have invented certain new and useful Improvements in Coupon-Cutting Devices; and I do hereby declare that the following is a full, clear, and exact description thereof.

10 My invention refers to cutting machines and has for its primary object to provide a simple economical and effective means for clipping rectangular coupons or tabs from the marginal edges of a sheet. Specific objects of my invention are:

15 To provide a pair of rectangular associated floating shear blades operating in conjunction with a fixed shearing-surface whereby the mitered edges of the coupon are smoothly severed from the sheet, the cut resulting in a clean sharp corner;

20 To provide means for attaching the blades to a plunger head so arranged that the mitered corners of the blades are normally spaced apart, with the straight cutting edges inclined obliquely relative to the fixed shearing-surface, whereby upon a downward or cutting movement of the said blades, they will progressively contact with the shearing 25 edges of the fixed surface to thus render them self-sharpening throughout their entire length, and at the same time, the mitered corner toes of the blades will close up to 30 form a continuous cutting edge, resulting in a clean, sharp separation of the coupon from the sheet;

35 To provide means for micromically adjusting the blades endwise, whereby the normally spaced beveled or mitered toes thereof, will come together at the finish of the cutting operation to insure a clean cut corner;

40 To provide yielding means for normally pressing the blades apart at their toe end, 45 from a fulcrum at the heel portions, whereby the cutting edges of the companion blades will normally overlap the base shearing-surfaces from a point near the heel portion of said blades.

50 With the above and other minor objects in view, the invention consists in certain peculiarities of construction and combination of mechanical elements, as herein described with reference to the accompanying 55 drawings and subsequently claimed.

In the drawings,

Figure 1 represents a central sectional elevation of a cutting machine embodying the features of my invention, the parts being shown in their normal position of rest.

60

Figure 2 is a cross section of the same, the section being indicated by line 2-2 of Figure 1.

Figure 2^A is a detail cross section through the heel of one of the cutting blades illustrating the means for anchoring the blade to a reciprocative plunger head.

65

Figure 3 is an inverted plan view of the machine with parts broken away, and in section, to more clearly illustrate certain structural features, the said view showing partly the angular or overlapped position assumed by the cutting knives at the start in their normal position, or at the starting point of a cutting operation.

70

Figure 4 is a similar fragmentary view, illustrating one corner of the machine and the position assumed by the knives or blades at the completion of the cutting stroke, whereby the mitered corners of said blades 80 are brought together to separate the tab or coupon cleanly at its corner, and

75

Figure 5 is a diagrammatic view of a sheet showing one arrangement of detaching coupons, wherein a certain number of such coupons have been removed from the lower right hand corner.

85

Referring by characters to the drawings, 1 represents a base, in the form of a hollow frame, provided at its upper face with 90 a shearing-surface 2, which surface for the convenience of the construction, in this instance is separable. The base is formed with an integral arm 3, which arm carries a spring controlled plunger 4, having attached 95 to its lower end a head 5, the same being illustrated in skeleton form, having a pair of front feet 6-6', and a rear foot 7. The skeleton head is also provided with a sleeve 8, which sleeve is reciprocatively guided 100 upon a pin 8' that extends from the arm 3. The head, as a whole, is encased in a suitable shell 9. The rear foot 7 and front foot 6' of the head are provided with studs 10-10' respectively, the same comprising anchors 105 for a loosely fitted side blade 11, said blade being provided with slightly elongated apertures through which the pins extend, to permit end play as best shown in Figures 1, 2^A and 3.

110

The heel portion *a*, of the side blade, which is attached to the foot 7 and the toe portion of said blade, which is attached to the foot 6', is pressed outwardly by means 5 of coil springs 12—12' respectively, whereby the lower obliquely disposed cutting edge 11" of said blade is yieldingly held in contact with the shearing-surface 2 at the heel end of said blade when the parts are in their 10 normal or inactive position.

Thus, it will be seen that the side blade, in conjunction with the lower cutting surface 2, forms a V-shaped mouth for the insertion of a sheet of paper, when it is desired 15 to sever a coupon therefrom. In order to sustain the cutting strain exerted upon the blades, the feet 7 and 6' are formed with offset lips 13—13' respectively, which lips engage the juxtaposed upper surfaces of 20 the blade as shown. The toe end of the blade is formed with a beveled edge 11", the same being arranged to swing inwardly and forming a cross mitered joint in connection with a corresponding beveled toe 25 edge 14" of an end blade 14. This end blade 14 is disposed at an approximate right angle to the side blade, and is anchored to the feet head 6 and 6' respectively in the same manner as that previously described, with reference 30 to the aforesaid side blade, the parts being lettered to correspond to the same mechanical elements associated with said side blade.

It should also be understood that the heel 35 portion *a* of the end blade contacts with the rectangular shearing-surface 2, in the same manner as that previously described in connection with the side blade, and that the lower cutting edge 14' of said blade is disposed obliquely with relation to the cutting 40 surface of the base to form a continuation of the feed mouth when the head is sustained in its upward, inactive, normal position. When the companion knives are assembled, 45 it will be noted that their associated springs will split the mitered toes apart and that said split, in effect, will fulcrum upon the heel of these knives at that point which the heels thereof engage the shearing-surface 50 faces 2. Thus the knives in their normal, inactive position will incline outwardly or overlap the rectangular shearing-surfaces of the base from their heel portions, whereby a positive shearing action will result, in 55 connection with both knives progressively along the line of their respective shearing surfaces when the head is depressed in a cutting operation.

It will also be observed that when the 60 knives are thus cutting and gradually retracting in opposition to their spring control, the mitered toes of the knives are gradually drawing together, and as best shown in Figure 4, at the end of the cut when it is 65 desired to sever the corner of the coupon or

tab cleanly. These mitered toes contact to form a closed rectangular knife, whereby there is no liability of a ragged edge occurring at the mitered corner of the coupon, and it is thereby cleanly severed. 70

It will also be observed that the knives throughout their entire length from heel to toe will be automatically sharpened at each cutting operation. In order to micromically adjust the gap between the toes of the 75 knives, whereby they will close up snugly, even though the knives were subjected to wear from sharpening. I provide set screws 15—15 which are in threaded union with the feet 7 and 6 and the heads of 80 which screws are adapted to engage the rear ends of their associated blades, whereby said blades can be moved slightly forward or back, as the case may require. By referring to the diagrammatic view of Figure 5, it will 85 be seen that when it is desired to sever a coupon ticket or the like from an integral sheet, the sheet is inserted under the blade carrying head and when the plunger is depressed, the side knife 11 will cut the coupon along toward line indicated at *Y*, while the end knife 14 will complete the right angular cut upon the line indicated at *x*. 90

While I have shown and described an exemplification of my invention, in all of its 95 structural features, it is understood that I may vary such details for construction within a fair interpretation of the claims, as may be put upon them by the skilled mechanician. 100

I claim:

1. In a cutting machine having a reciprocative head, a base provided with a rectangular shearing-surface; the combination of a pair of rectangularly positioned blades 105 carried by the head having their shearing edges obliquely disposed with relation to the base shearing-surface, the heels only of which blades normally engage said shearing surface, spring means for normally 110 separating the toes of the aforesaid blades whereby the lower cutting edges thereof overlap the rectangular shearing-surfaces of the base, and whereby the knives, when cutting progressively sever 115 from heel to toe and simultaneously contract, causing the toe portions to come together to form an unbroken corner cutting surface, in the completion of the cutting stroke of the blades. 120

2. In a cutting machine having a reciprocative head, and a hollow base provided with inner rectangular shearing-surfaces, the combination of a pair of rectangularly disposed knives associated with the head, each 125 knife being provided with an obliquely disposed lower cutting face and a mitered toe, yielding means carried by the head for independently operating the knives therefrom starting from a heel point of contact be- 130

- between the lower cutting edges of the knives and the base shearing-surface, when the parts are in their normal inactive position, and means associated with the head for supporting the knives to permit play of the same.
3. A cutting machine comprising a base having a rectangular shearing-surface at its upper edge, a rectangular reciprocative head positioned above the shearing-surface, a pair of knives associated with the head having obliquely disposed cutting edges adapted to engage the shearing-surface of the base, pins for loosely supporting the knives in connection with the head, springs interposed between the inner face of the knives and head, whereby said knives are forced outwardly from a shearing contact point between the cutting surfaces of the blades at their heel ends, and means associated with the head for longitudinally adjusting the blades.
4. A cutting machine comprising a base having a rectangular shearing-surface at its upper edge, a reciprocative head positioned above the shearing-surface, a pair of rectangularly disposed transversely yieldable knives associated with the head, having obliquely disposed cutting edges adapted to engage the shearing-surface normally at a slight angle thereto, whereby said knives are forced inwardly against the shearing-surface from their heel ends in a cutting operation.
- In testimony that I claim the foregoing I have hereunto set my hand at Manitowoc 35 in the county of Manitowoc and State of Wisconsin.

HENRY DETJEN.
